UNITED STATES PATENT OFFICE

91,375

DESIGN FOR A TEXTILE FABRIC OR SIMILAR ARTICLE

August Von Eisenbarth, Bronxville, N. Y.,
assignor to J. Oltarsh, New York, N. Y.

Application December 5, 1933. Serial No. 49,962

Term of patent 3½ years

To all whom it may concern:

Be it known that I, AUGUST VON EISENBARTH, a citizen of the United States, residing at 59 Eton Road, Bronxville, New York, have invented a new, original, and ornamental Design for a Textile Fabric or Similar Article, of which the following is a specification, reference being had to the accompanying drawing, forming a part thereof.

The figure is a plan view of a textile fabric showing the complete width of my new design.

The dot and dash lines on the drawing outline substantially the design unit, which unit is repeated in regular succession as indicated by the extensions beyond the unit boundaries.

I claim:

The ornamental design for a textile fabric or similar article as shown and described.

In testimony whereof I have signed this specification.

AUGUST VON EISENBARTH.
